US0D1044869S

(12) **United States Design Patent** (10) **Patent No.:** **US D1,044,869 S**
(45) **Date of Patent:** **** Oct. 1, 2024**

(54) **TROLLING MOTOR MOUNT**

(71) Applicant: **NAVICO, INC.**, Tulsa, OK (US)

(72) Inventor: **Paul Bailey**, Auckland (NZ)

(73) Assignee: **NAVICO, INC.**, Tulsa, OK (US)

(**) Term: **15 Years**

(21) Appl. No.: **29/720,498**

(22) Filed: **Jan. 14, 2020**

Related U.S. Application Data

(63) Continuation of application No. 29/624,312, filed on Oct. 31, 2017, now Pat. No. Des. 886,865.

(57) **CLAIM**

The ornamental design for a trolling motor mount, as shown and described.

DESCRIPTION

FIG. 1 is a front perspective view of a trolling motor mount showing my new design;

FIG. 2 is a front view of the trolling motor mount of FIG. 1; FIG. 3 is a rear view of the trolling motor mount of FIG. 1; FIG. 4 is a left side view of the trolling motor mount of FIG. 1;

FIG. 5 is a right side view of the trolling motor mount of FIG. 1;

FIG. 6 is a top view of the trolling motor mount of FIG. 1; FIG. 7 is a bottom view of the trolling motor mount of FIG. 1; and,

FIG. 8 is a front perspective view of the trolling motor mount of FIG. 1 shown with a trolling motor head.

The broken lines illustrate unclaimed portions of the trolling motor mount or environment and form no part of the claimed design.

1 Claim, 8 Drawing Sheets
